UNITED STATES PATENT OFFICE.

ERNEST G. H. SCHENCK, OF NEW YORK, N. Y.

DESIGN FOR A CUT STONE.

43,724.

Specification for Design.

Patented Mar. 18, 1913.

Application filed April 24, 1911. Serial No. 623,119. Term of patent 14 years.

To all whom it may concern:

Be it known that I, ERNEST G. H. SCHENCK, a subject of the King of Belgium, residing at New York, in the county of New York and State of New York, have invented a new, original, and ornamental Design for Cut Stones, of which the following is a specification, reference being had to the accompanying drawing, forming part thereof.

In the drawings which show my design somewhat enlarged from the way it actually appears on the stone, Figure 1 is a plan view of a stone cut in accordance with my design; Fig. 2 is a side elevation of the same, showing the lower portion of said stone conventionally by dotted lines; Fig. 3 is a perspective view of said stone showing my design looking from above.

In my design the central portion of the upper side of the stone instead of having

a central table of comparatively large area as in the ordinary "brilliant" is cut in the form of a plurality of quadrangular panels or facets, and the surrounding border portion of the upper side is cut into a broken series of triangular facets resembling very closely the ordinary brilliant cutting. At the corners formed by the meeting edges bounding the quadrangular panels of the central portion are formed very much smaller corner bevels which are, however, scarcely discernible in the actual stone when cut.

I claim:

The ornamental design for a cut stone, as shown and described.

ERNEST G. H. SCHENCK.

Correction in Design Letters Patent No.
43,724.

It is hereby certified that in Letters Patent No. 43,724, granted March 18, 1913, upon the application of Ernest G. H. Schenck, of New York, N. Y., for "a Design for a Cut Stone," an error appears in the drawing requiring correction as follows: Figure 2, the lower portion of the stone should be *represented in dotted lines* in accordance with the description of that Figure contained in the specification; and that the said Letters Patent should be read with this correction therein that the same may conform to the record of the case in the Patent Office.

Signed and sealed this 15th day of April, A. D., 1913.

[SEAL.]

C. C. BILLINGS,

Acting Commissioner of Patents.
